DESK SET

Carey Garfield Gregory, Los Angeles, Calif.

Application August 10, 1938, Serial No. 224,215

9 Claims. (CL. 120—59)

My invention relates broadly to desk sets of the hydrostatic pressure type and more particularly to an improved and simplified construction of desk set.

5 One of the objects of my invention is to provide a construction of desk set embodying the principle of hydrostatic pressure in the feeding of the required ink supply and in which standard size bottles of ink nationally distributed and assembled on the open market may be equipped with a hydrostatic feed and readily mounted in position in a desk set for supplying ink to a dip pen.

10 Another object of my invention is to provide a simplified and inexpensive construction of hydrostatic pressure feed type of desk set which includes an integrally molded receptacle and dip pen guide with means for strapping an ink bottle in inverted position in the receptacle for continuously feeding ink to a dip pen insertable through the dip pen guide.

15 Still another object of my invention is to provide a simplified construction of hydrostatic pressure operated desk set in which a standard size ink bottle may be readily maintained in inverted position in a receptacle by means of a strapping device yieldably engageable with opposite walls of the receptacle for controlling the feeding of ink to a dip pen guide.

20 A further object of my invention is to provide a construction of hydrostatic feed adapted to be engaged upon the neck of an ink bottle adapted to be supported in inverted position in a hydrostatic desk set and operating to control the flow of ink supplied from the ink bottle to the desk

25 set.

Other and further objects of my invention reside in the improved and simplified construction of hydrostatic desk set, set forth more fully in

30 the specification hereinafter following by reference to the accompanying drawings, in which:

Figure 1 is a perspective view of the improved desk set of my invention; Fig. 2 is a vertical longitudinal sectional view through one form of desk set embodying my invention; Fig. 3 is a vertical sectional view taken on line 3—3 of Fig. 2 and line 3—3 of Fig. 4; Fig. 4 is a horizontal transverse sectional view taken on line 4—4 of Fig. 2; Fig. 5 is a horizontal transverse sectional view taken on line 5—5 of Fig. 2; Fig. 6 is a transverse sectional view of one construction of hydrostatic feed cap taken on line 6—6 of Fig. 7 which may be substituted upon the neck of the ink bottle for the usual closure cap; Fig. 7 is a plan view of the hydrostatic feed cap illustrated in

Fig. 6; Fig. 8 is a schematic view showing the manner of starting the feeding of ink from the ink bottle when assembled in the desk set; Fig. 9 is a vertical sectional view through a modified form of desk set embodying my invention; Fig. 10 is a horizontal transverse sectional view through the desk set illustrated in Fig. 9 taken on line 10—10 of Fig. 9; Fig. 11 is a vertical sectional view through a further modified form of desk set embodying my invention; Fig. 12 is a fragmentary sectional view taken through a further modified form of hydrostatic feed attachment for an inverted ink bottle; Fig. 13 is a fragmentary sectional view of a further modified form of hydrostatic feed device for an inverted ink bottle; and Fig. 14 is a still further modified form of hydrostatic feed for an inverted ink bottle.

My invention is directed to that class of hydrostatic desk set represented generally in my Patents Nos. 2,026,529, of January 7, 1936, for Combined inkwell and bottle, and 2,112,907, of April 5, 1938, for Desk set. In the arrangement of my present invention, I provide a construction of molded receptacle and dip pen guide which may be inexpensively manufactured on a quantity production basis. The portion of the desk set of my present invention that constitutes a receptacle is provided with supporting means arranged interiorly thereof, forming abutments against which an ink bottle equipped with a special construction of hydrostatic feed may be mounted in inverted position. The receptacle is so designed that standard shapes and sizes of ink bottles may be readily mounted therein. It is only necessary to remove the usual closure cap from the standard ink bottle and substitute the special form of hydrostatic feed embodied in the structure of my invention and mount the ink bottle in inverted position on the abutments provided for that purpose interiorly of the receptacle. In order to maintain the ink bottle with relation to the receptacle, I provide a spring device which extends transversely of the ink bottle and yieldably engages opposite sides of the receptacle for maintaining the ink bottle in position. In the event that the desk set may be lifted by grasping the ink bottle, no injury results as the spring device maintains the ink bottle in position with respect to the receptacle. The hydrostatic feed employed upon the ink bottle may be a foraminated screw cap, an apertured stopper device, a cap having a central protuberance, a stopper device having a central protuberance, or a cap and stopper device hav-

ing tubular protuberances which are eccentric with respect to the center of the cap or stopper device.

Referring to the drawings in detail, reference character 1 designates the molded base of the desk set having a projection 2 extending laterally therefrom. The molded base is integrally apertured for receiving a molded receptacle 3. The molded receptacle 3 includes a vertically extending wall structure and an integrally formed dip pen guide indicated generally at 4. The dip pen guide has its axis formed substantially on an acute angle with respect to the vertical axis of the receptacle 3. The dip pen guide has a hollow bore consisting of an internal cylindrical portion 5, a frusto-conical dip pen guide portion 6, a frusto-conical pen guide portion 7 and a cylindrical port 8 extending between the interior of the receptacle 3 and the frusto-conical portion 7 of the dip pen guide. A dip pen indicated generally at 9 is adapted to be inserted through the dip pen guide which includes a peripheral flange 10 adapted to seat against the frusto-conical portion 6 of the dip pen guide and a cylindrical portion 11 extending to the rounded annular bead 12 at the extremity of cylindrical portion 11. The penholder provides mounting means for the pen feed 14 which serves to secure the penpoint 15 in position. The penholder 9 when resting in the pen guide 5 in idle position has the flange 10 thereof in abutment with the frusto-conical portion 6 of the pen guide forming a dust-tight closure for the pen guide. When fully inserted in the dip pen guide as represented in the drawings, Figs. 1, 2, 9 and 11, the penpoint 15 is submerged in the pool of ink 13 in the base of receptacle 3.

The receptacle 3 is provided with a plurality of supporting abutments disposed interiorly thereof, as indicated at 16, 17 and 18. In addition to these abutments, there is an additional abutment 19 which is bifurcated to form both a supporting abutment and an ink channel between the port 8 in the dip pen guide and the bottom of the receptacle.

The supporting abutments 16, 17, 18 and 19 are arranged in diametrically opposed relation and provide supporting means for an inverted ink bottle equipped with the hydrostatic pressure feed 50 means of my invention.

In Figs. 1-8, I have shown an ink bottle 20 which is of the familiar rectangular shape nationally distributed and readily available in retail establishments throughout the United States. The usual closure cap is removed from a screw threaded neck 21 of bottle 20 and in lieu thereof, a foraminated cap 22 is screwed over the screw threads 21 of the cap. The foraminated cap 22 is apertured at 23 for permitting the controlled supply of ink from the ink bottle to the pool 13 in the base of receptacle 3. The receptacle 3 is provided with lugs 24 which are molded integrally with the upper portion of the wall of receptacle 3 with grooves 25 formed in lugs 24. A spring device 26 in the form of a band having substantially hook shaped yieldable ends 27 is arranged to be sprung over the ink bottle 20 so that the flat intermediate portion of spring 26 tends to continuously place the ink bottle in inverted position against the supporting abutments 16, 17, 18 and 19. The hook shaped resilient ends 27 engage through the grooves 25 under the lugs 24, thereby maintaining the ink bottle 20 rigidly in position. Even though the ink bottle 20 should 75 be grasped by the fingers and the desk set thus

raised, the spring 26 maintains substantially locked engagement with lugs 24 so that the desk set including the ink bottle is raised as a unit without danger of spilling the ink. As shown in Fig. 8, the hydrostatic feed of the ink may be readily started by tilting the desk set at a slight angle.

In Figs. 9 and 10, I have illustrated the desk set of my invention as embodying an ink bottle of the cylindrical type. The cylindrical bottle is indicated generally at 28 having a screw threaded neck 29 from which the customary closure cap is removed and into which a substantially flat stopper 30 is inserted. The substantially flat stopper 30 is apertured at 31 for the hydrostatic feed of ink from the ink bottle 28 to the pool 13 in receptacle 3. The stopper 30 has the annular peripheral edge thereof provided with resilient soft material 32 which yieldably engages the interior annular wall of the neck of bottle 28, thereby establishing a leak-proof joint between the stopper and the ink bottle.

In Fig. 11 I have illustrated a modified form of hydrostatic feed as applied to the threaded neck 29 of ink bottle 28. The hydrostatic feed in this form of my invention includes a screw threaded member 33 engageable with screw threads 29 with a central tubular protuberance 34 depending therefrom. The central protuberance 34 is apertured in one side at 35. Protuberance 34 is cut-off at an angle represented at 36 so that the shortest longitudinal dimension of protuberance 34 is substantially opposite aperture 35.

In Fig. 12, I have shown another modified form of hydrostatic feed in which stopper 37, provided with annular packing ring 38 of relatively soft material, is mounted interiorly of the neck 29 of bottle 28. The stopper 37 has a central tubular protuberance 39 thereon. The protuberance 39 is cut off at an angle indicated at 41. An aperture 40 is provided in the protuberance 39 along the longest longitudinal dimension of protuberance 39.

In order that a fresh supply of ink may be delivered immediately adjacent the point 15 of the dip pen, I may employ a modified form of hydrostatic feed as represented in Fig. 13 wherein screw member 33a has tubular protuberance 34a extending therefrom in a position eccentric to the center of the cap. By this arrangement the bottle 28 may be angularly shifted to bring the tubular protuberance in close proximity to the point 8 of the dip pen. The end of protuberance 34a is shaped as indicated at 36a and the protuberance is apertured at 35a to insure hydrostatic feed of a new supply of ink immediately adjacent the end of the dip pen.

As indicated in Fig. 14, a stopper 37a secured in position by yieldable peripheral edge portion 38a may be provided with a tubular protuberance 39a which is eccentric with respect to the center of the stopper 37a. Tubular protuberance 39a is provided with an aperture 40a and an angularly cut-off end portion 41a. The fact that the tubular protuberance is eccentric with respect to the center of the cap 37a allows the ink bottle to be shifted to such position as will insure a fresh supply of ink at all times to the end of the dip pen.

Venting of the desk set to facilitate the hydrostatic feeding of the ink supply is accomplished by virtue of the space existing between the side walls of the inverted ink bottle and the interior walls of the receptacle 3, whereby atmospheric pressure is maintained with respect to the surface 75

of the pool of ink in the base of receptacle 3. A condition of equilibrium is reached in hydrostatic pressure when the level of the pool of ink 13 reaches a plane in both the receptacle 3 and the bore of the pen guide 4 coincident with the plane of the foraminated cap 22 in the form of my invention illustrated in Figs. 1-8, or the plane of the insert shown in Figs. 9-10, or the upper limit of aperture 35, 40, 35a or 40a in the forms of my invention shown in Figs. 11, 12, 13 and 14, respectively. As heretofore noted, the hydrostatic feeding of the ink may be started by tipping the desk set as indicated generally in Fig. 8.

While I have described my invention in certain of its preferred embodiments, I desire that it be understood that modifications may be made and that no limitations upon my invention are intended other than may be imposed by the scope of the appended claims.

20 What I claim as new and desire to secure by Letters Patent of the United States is as follows:

1. A desk set comprising in combination a frame structure, an ink bottle adapted to be mounted in inverted position in said frame structure, a reservoir for ink within said frame structure, a dip pen guide and well formed integrally with said frame structure and terminating in a position immediately adjacent said ink reservoir and in connection therewith, and a cap member engageable with the neck of said ink bottle, said cap member having a port therein substantially eccentric to the central axis of the ink bottle and arranged with the outlet of said port in close proximity to the terminus of said pen guide and well for directing a flow of ink to said ink reservoir in a position immediately adjacent the terminus of said pen guide and well for maintaining a fresh supply of ink under hydrostatic control for the end of a dip pen projecting into said pen guide and well.

2. A desk set comprising in combination a frame structure, an ink bottle adapted to be mounted in inverted position in said frame structure, a reservoir for ink within said frame structure, a dip pen guide and well formed integrally with said frame structure and terminating in a position immediately adjacent said ink reservoir and in connection therewith, and a plug member engageable with the neck of the ink bottle, said plug member being apertured in a position substantially eccentric to the central axis of said ink bottle and arranged with the aperture in close proximity to the terminus of said pen guide and well for delivering a fresh supply of ink under hydrostatic control to said ink reservoir in a position immediately adjacent the projecting point of a dip pen inserted in said pen guide and well.

3. A desk set comprising in combination a frame structure terminating in an ink reservoir and having an upwardly directed rectangular guide portion, a cubical ink bottle mounted in inverted position through the guide portion of said frame structure, a pen guide extending through said frame structure and terminating within said ink reservoir for maintaining a dip pen in position with respect to said frame structure, means associated with the neck of said ink bottle for restricting the flow of ink from said ink bottle to said ink reservoir for delivery to a dip pen introduced into said pen guide, and a substantially rectilinear U-shaped flexible strap member contiguous with upper side and top portions of said inverted cubical ink bottle and engageable with opposite sides of said frame structure for main-

taining said ink bottle in set position with respect to said frame structure.

4. A desk set comprising in combination a frame structure terminating in an ink reservoir and having an upwardly directed rectangular guide portion, a cubical ink bottle mounted in inverted position through the guide portion of said frame structure, a pen guide extending through said frame structure and terminating within said ink reservoir for maintaining a dip pen in position with respect to said frame structure, and a relatively narrow band member secured to one side of said frame structure and extending contiguous with upper side and top portions of said inverted ink bottle and detachably engageable with the opposite side of said frame structure for maintaining said ink bottle in set position.

5. In a desk set, a frame structure having an ink reservoir in the base thereof and an ink bottle receiving portion in the top thereof, an ink bottle adapted to be mounted in inverted position in said frame structure, a pen guide in said frame structure for supporting a dip pen in a position projecting into said ink reservoir, and a plug member insertable into the neck of said ink bottle, said plug member having an apertured protuberance thereon disposed substantially eccentric to the center of said ink bottle and said ink reservoir and arranged in a position immediately adjacent the terminus of said pen guide for delivering a continuous supply of fresh ink under hydrostatic control to the projecting point of a dip pen introduced through said pen guide

6. In a desk set, a receptacle having a dip pen guide formed at one side thereof, abutment supports mounted interiorly of the base of said receptacle and including a bifurcated abutment support disposed in said receptacle immediately adjacent the connection of said dip pen guide therewith and forming a channel for the passage of ink from said receptacle into said dip pen guide, an ink bottle having a hydrostatic feed device connected therewith and projectible into the base of said receptacle when said ink bottle is mounted in inverted position on said abutment supports.

7. In a desk set, a receptacle having a dip pen guide formed at one side thereof, abutment supports mounted interiorly of the base of said receptacle and including a bifurcated abutment support aligned with said pen guide and forming an ink channel to said pen guide in said receptacle, an ink bottle adapted to be mounted in inverted position in said frame structure, and a closure member for said ink bottle having a port therein substantially eccentric to the central axis thereof, said ink bottle being supported by abutment of said closure member with said abutment supports, and said closure member being arranged with the outlet of said port in alignment with said bifurcated abutment support for delivering a fresh supply of ink directly to said ink channel for the projecting point of a dip pen inserted in said pen guide.

8. In a desk set, a frame structure terminating in an ink reservoir and having an upwardly directed rectangular guide portion for receiving a cubical ink bottle in inverted position, and a substantially rectilinear inverted U-shaped resilient strap member detachably engaged with opposite sides of said frame structure and engageable contiguous with upper side and top portions of an inverted cubical ink bottle supported in the guide portion of said base for maintaining a cubical ink

bottle in set position with respect to said frame structure.

9. In a desk set, a unitary frame member comprising a receptacle portion having abutment supports therein for supporting an ink bottle in inverted position, and a pen guide formed at one side of said receptacle portion with an open passageway extending through the bottom of said

pen guide to said receptacle portion, certain of said abutment supports constituting limiting wall elements in said receptacle portion on either side of said passageway and providing a restricted path for fresh ink supplied to said pen guide from an ink bottle supported in said receptacle portion.

CAREY GARFIELD GREGORY.
